UNITED STATES PATENT OFFICE.

HENRY SMITH, OF LONDON, ENGLAND.

MEANS FOR OPENING OR CLOSING SLIDING WINDOWS AND THE LIKE.

Application filed November 2, 1925, Serial No. 66,374, and in Great Britain December 3, 1924.

This invention relates to windows and like sliding members adapted to be opened or closed by aid of a weight or resilient means.

5 The invention is particularly applicable to windows for motor cars, trains, ships' cabins or saloons and the like. It may also be employed in connection with sash windows for buildings or horizontally moving 10 sliding windows, doors, panels or shutters, which may hereinafter be conveniently classed as "windows".

The object of the invention is to provide 15 improved means for opening and closing windows so that such may be locked or maintained in position when opened or closed and arrested and locked or held in any intermediate position. It is also an object of the invention to provide means where- 20 by the arrestation and locking of the window may be automatic or controllable in either or both directions of movement.

According to the invention the arresting 25 and locking means comprise a member adapt- ed to move or rotate in one direction or an- other as the window is opened and closed, an abutment element or device and a shoe or wedge operating between the abutment and the member in such a manner that the rela- 30 tive movement and contact between the parts causes the shoe to be drawn into increasing frictional contact with the member as it moves in one direction, with a wedge-like action, while in the other direction of move- 35 ment the member and shoe slide relatively with little or no retarding effect.

The arresting or locking means may be 40 combined with a spring (preferably a volute or coiled spring) adapted to cause the move- ment of the window in one direction, asso- 45 ciated with a transverse shaft operatively connected with the window so that upon the rotation of the shaft under the influence of the spring the window is raised or moved across its opening and, conversely, as the window is lowered (or moved backward) the spring is tensioned.

A feature of the invention lies in the com- 50 bination of the spring raising or lowering means with the arresting and locking de- 55 vice so that the latter operates automatically to arrest and temporarily lock the window in any position in which it may be moved by the operator against the tension of the spring, the arrangement being such that upon relieving the pressure or effort dis-

placing the window, the action of the spring, which normally tends to return the window, causes the locking means (for example, the brake shoe) automatically to come into op- 60 eration (viz by reason of the shoe wedging between the abutment and its associated member).

The means adapted for raising or lowering 65 and locking the window may be mounted upon a panel which is applied transversely of the window, thereby facilitating the ap- 70 plication of the invention from a construc- tional point of view and enabling such to be more readily applied to existing windows. 75

The locking device may be under the con- 80 trol of a person desiring to open or close the window by aid of a handle, knob or other manipulating device adapted to act upon the shoe or an associated part to adjust its po- 85 sition or otherwise to cause it to function as desired. The manipulating means should preferably be provided with a limited ad- justment movement in order that the control may be confined to the purpose required or so 90 that conditions cannot arise that allow the window free movement, such as might cause damage or injury.

In the accompanying drawings:—

Figure 1 is a sectional side elevation of a 85 motor car or like door fitted with a sliding window and illustrating window raising and controlling means applied thereto according to the invention.

Figure 2 is an enlarged section of the part 90 adjacent the sill of the window and door seen in Figure 1.

Figure 3 is a sectional side elevation taken through the middle portion of the arrange- 95 ment shown in Figure 2.

In carrying the invention into effect ac- 100 cording to one convenient mode as applied, by way of example, to vertically sliding windows for a motor car door, the window A may be mounted in the door B and adapt- 105 ed to slide in guide grooves according to usual practice. The window frame adja- cent or in the region of the sill C (Figure 1) is provided with a panel (of wood, metal or other suitable material) or box-like casing 110 1 extending from side to side thereof. This panel member may be made detachable from the permanent framework for instance at the upper edge. Within or at the back of the panel member 2 suitable bearings are 115 provided which are adapted to carry a ro- tatable transverse shaft. 3.

2
Towards each end or in any convenient position on this shaft, a pulley or roller element 4 is rigidly mounted. These pulley elements may be suitable for the reception 5 of a flexible element such as a cord, indicated at 5, one end of which is attached to the pulley and the other end to the lower edge of the window. It is preferred that the cord should be wound up on the pulley or roller 10 in a series of laterally adjacent laps.

Where a belt or wire is employed it is preferred that such should be connected to brackets, stays or projections 6 formed upon or carried by a metal or other channel-shaped piece 6^a, adapted to extend across 15 and receive the bottom edge of the window glass.

The window frame is provided with the usual guiding grooves for the reception of 20 the lateral margins of the window or window glass so that the latter may slide vertically therein and it will be understood that upon rotation of the transverse shaft in one direction, the window will be raised 25 through the pulley or like means 4 and cords 5. The force adapted to cause the rotation of the transverse shaft may be derived from a spring or springs which act in a manner well known to cause the raising or lowering 30 of the window according to the direction in which the spring is adapted to operate.

According to the preferred mode the inner end of a volute spring 7 is anchored to 35 a sleeve or collar 7^a fixed upon the transverse shaft 1 while the outer end is anchored to the panel or door fixture.

In operation it will be understood that by 40 depressing or lowering the window, the volute spring is tensioned or wound up and when pressure is relieved from the window the latter will unwind, causing the rotation of the shaft and the raising of the window according to a manner already well known.

45 In order to control the movement of the window under the influence of the spring, a brake drum member 8 is rigidly formed upon or fixed to the shaft, and a brake shoe 9 adapted to co-operate with the drum. This 50 shoe is preferably of elongated arcuate wedge shape having a concave inner and a convex outer surface. The inner surface may be lined with the material known under the registered trade mark as "Ferodo" or other 55 suitable brake surface material may be provided.

An abutment 10 is provided for the brake shoe, which may be formed or mounted upon a casing or bracket member, such as 9^a, and 60 arranged so that the brake shoe when adjusted to a contact position against the drum 8 is displaced or drawn in between the abutment and the drum brake surface with a wedging action as the drum rotates in 65 one direction but which in the other direc-

tion of rotation allows the drum to slide over the shoe surface.

The shoe is connected to a spring-controlled plunger 10, the spring 10^a of which may be disposed in a cylindrical extension 70 of the casing or bracket 9^a, the spring 10^b being adapted constantly to tend to push the shoe in between the abutment and the drum. The casing may be provided with a screwed cap 10^c in order to adjust the 75 compression of the spring or, alternatively, any other suitable means may be employed whereby the adjustment of the brake shoe spring 10^a may be effected. The shoe 9 may be directly connected to the plunger 80 10 or a link may be provided for this purpose.

It is of importance to provide a device whereby the extent of the outward movement and, preferably, the inward movement of the shoe, may be limited, and to this end the plunger or plunger rod connected to the shoe may be provided with or operated in conjunction with a stop e' or other like means for confining the movement of the shoe in the outward or both directions. Any suitable means may be provided for controlling or adjusting the position of the shoe by an operator. These means may be of the type which requires manipulation to effect displacement of the shoe in one direction but which allows the shoe to return when released, the displacement of the brake shoe being co-extensive 95 with the period for which the operator holds the manipulating means.

According to a simple form of manipulation control means, a pivoted lever 11 having a knob or handle 11^a may be connected at one end through a slot 11^b with the end of the plunger 10. When the knob 11^a is pressed the shoe 9 is withdrawn so that the drum 8 is disengaged and the shaft 3 is free to be rotated by the spring 7. When pressure is withdrawn from the knob the 105 spring 10^a restores the lever 11 and the shoe to its initial or inward position so that the rotation of the drum 8 and the shaft 3 is arrested.

The initial or setting up adjustments of 110 the device should be such that when the manipulating means is operated to withdraw the shoe, it resides in a position in which it is out of contact with the drum or, alternatively, still in contact therewith but so that 115 the drum will rotate relatively thereto with little friction so that movement in this direction is comparatively unrestrained or only sufficient braking effect should take place as to enable or ensure that the window rises at a suitable rate and not too quickly. Further, the adjustment must be such that when the rotation of the drum is in the opposite direction and conditions are otherwise 120 favourable, the shoe, by reason of the con- 125 130

tact and relative movement, is drawn more or less sharply in between the abutment and the drum, developing an increasing frictional restraint upon the movement thereof which almost immediately is sufficient to arrest the rotation of the drum and check the window. The inward limit of movement of the shoe should be such as to prevent the latter from being drawn into a position in which it might become jammed and could not readily be retracted by the manipulative means.

In operation, assuming that the window is in the lowered position, the spring in its tensioned condition and the brake shoe in the retarding or locking position the window may be caused, by a manipulative action on the part of the operator effecting the withdrawal of the shoe, to rise under the force of the shaft spring, the rate of movement being controlled according to the degree of withdrawal of the brake shoe. When the window reaches the top the manipulating means may be released if such are of the character which requires the attention of the operator while the window is rising, or the manipulating device is re-adjusted if such be of the kind that requires adjustment in both directions. Alternatively, the spring may be relied upon to maintain the window in the fully raised or closed position while the manipulating means are left in a position in which the shoe is away or partially away from the drum.

While the window is rising it may be checked in any intermediate position by a suitable operation or release of the manipulating means.

When it is desired to lower the window the application of a downward pressure upon the window itself or upon an appropriate handle causes the window to descend against the tension of the spring. The relief of this pressure when the window reaches its fully open position or in any intermediate position between the fully closed and fully open position, causes the spring to react to tend to raise the window but owing to the automatic operation of the brake shoe this tendency is immediately checked by reason of the brake shoe intervening between the abutment and the brake drum under the action of the shoe spring, the pressure of the window raising spring causing the retarding action of the shoe to operate as a lock.

When it is desired to raise the window from an intermediate position, the brake shoe is withdrawn by the manipulating means and the window will rise under the action of the spring. Should it be desired to lower the window, the application of pressure thereto will cause the rotation of the shaft and drum to be reversed and the shoe automatically to be set back, whereby the

window may be pushed down to its fully open position when the automatic locking characteristics again come into play.

Having now described my invention what I claim as new and desire to secure by Letters Patent is:

1. A device for opening and closing windows and the like of the kind described comprising motive means for causing the movement of the window, a rotary member operatively connected with the window, a brake member adapted to have a wedge-like braking action against the rotary member to produce a braking and arresting action thereon in one direction of rotation and adjustable control means adapted to determine the operative function of the brake member.

2. A device for opening and closing windows and the like of the kind described comprising motive means for causing the movement of the window, a rotary brake member, an operative connection between the rotary brake member and the window, a brake shoe adapted to contact with the rotary brake member, abutment means associated with the rotary brake member so that the shoe may operate between the abutment means and the rotary brake member with a wedging action in one direction of rotation and adjustable control means for determining the operative functions of the brake shoe.

3. A device for opening and closing windows of the kind described comprising a rotary member adapted to rotate first in one direction and then in the other, and operatively connected with the window, spring motive means for closing the window and causing the rotation of the rotary member in one direction, brake means adapted to cooperate with the rotary member and capable of arresting such in one direction of rotation thereof while in the other direction said brake means offer little frictional resistance, and adjustable control means for relieving the arresting action of the brake, the arrangement being such that by the application of manual power to the window it may be pushed open against the action of the spring motive means and such that the arresting action of the brake means automatically comes into operation upon the cessation of such opening movement by the reactive effect of the motive means so that the window is held in any adjusted position.

4. A device for opening and closing windows and the like of the kind described comprising motive means for causing the movement of the window, a rotary member adapted to rotate first in one direction and then in the other, and operatively connected with the window, a brake member adapted to have a wedge-like action against the rotary member to produce a braking and arresting action thereon in one direction of rotation, adjustable control means adapted

to determine the relief of the arresting action of the brake member, and means adapted to ensure frictional contact between the brake member and the rotary member when the window is being moved by the motive means so as to prevent unrestrained movement liable to cause damage.

5. A device for opening and closing windows and the like of the kind described comprising motive means for causing the movement of the window, a rotary brake member, an operative connection between the rotary brake member and the window, a brake shoe of curved wedge form adapted to contact with the rotary brake member, a curved abutment associated with the rotary brake member so that the curved shoe may operate with a wedge-like action between the rotary brake member and the curved abutment upon which it is adapted to slide and adjustable means for determining the operative functions of the brake shoe.

6. A device for opening and closing windows of the kind described comprising motive means for causing the movement of the window, a rotary member adapted to rotate first in one direction and then in the other and operatively connected with the window, a brake member adapted to have a wedge-like action against the rotary member to produce a braking and arresting action thereon in one direction of rotation, adjustable control means for moving the brake member away from the rotary member, and a stop device for limiting the permissible movement of the brake member away from the rotary member so that it may still contact therewith in the withdrawn position to have a frictional restraining action operating against the tendency of the motive means to return the window.

7. A device for opening and closing windows of the kind described comprising motive means for causing the movement of the window, a rotary member adapted to rotate first in one direction and then in the other and operatively connected with the window, a brake member of wedge-shape, spring

means for thrusting the brake member into engagement with the rotary member, means for adjusting the tension of said spring and adjustable control means for withdrawing said brake member.

8. A device for opening and closing windows of the kind described comprising motive means for causing the movement of the window, a rotary member adapted to rotate first in one direction and then in the other and operatively connected with the window, a brake member of wedge-shape thrust into engagement with the rotary member by spring means, means for adjusting the tension of said spring, adjustable control means for withdrawing said brake member and a stop device for limiting the extent to which the brake member may be withdrawn to prevent its freeing the rotary member entirely.

9. A device for opening and closing windows and the like of the kind described comprising motive means for causing the movement of the window, a rotary member operatively connected with the window, a brake member adapted to have a wedge-like braking and arresting action against the rotary member in one direction of rotation and an adjustable control having a lever action for determining the position of the brake member.

10. A device for opening and closing windows and the like of the kind described comprising motive means for causing the movement of the window, a rotary member operatively connected with the window, a brake member adapted to have a wedge-like braking and arresting action against the rotary member in one direction of rotation, and adjustable control means consisting of a handle having a partial rotary movement and adapted to exert a leverage for withdrawing the brake member in a direction away from the rotary member.

In testimony whereof I have signed my name to this specification.

HENRY SMITH.
